Walter Griebel, Karl-Heinz Breite, and Heinrich Wies-
mair, Dermbach, Germany, assignors to VEB Rhonglas-
werk Dermbach, Dermbach, Germany

Filed Nov. 26, 1968, Ser. No. 14,680

Claims priority, application Italy July 15, 1968

Term of patent 7 years

Int. Cl. D7—99

U.S. Cl. D44—1

FIG. 3

FIG. 2

FIG. 1

FIG. 4

FIG. 5

FIG. 1 is a perspective view of a combined insulated food container, cup and spoon, showing our new design; FIG. 2 is a rear elevational view;

FIG. 3 is a side elevational view; FIG. 4 is a front elevational view; and FIG. 5 is a top plan view.

We claim:

The ornamental design for a combined insulated food container, cup and spoon, substantially as shown.
